DEGASSING APPARATUS FOR PLATEN PRESSES

Thomas P. Tapper, Prospect Park, Pa., assignor to Baldwin-Lima-Hamilton Corporation, a corporation of Pennsylvania

Application April 9, 1948, Serial No. 20,063

3 Claims. (Cl. 144—281)

1

This invention relates generally to multiple platen presses for applying pressure and heat to sheet-like material, and more particularly to means for preventing the displacement of such material between the two uppermost platens during the breathing or degassing operation.

As is well understood in the art, a press of this type usually has a series of movable platens and a topmost stationary platen suitably insulated from the press crosshead. When the press stands open, all the movable hot plates or platens rest on supports in spaced relationship to each other. After material to be compressed and heat-treated has been placed between the spaced platens and centered thereon, the press is closed by an upwardly moving hydraulically operated ram of the press. After applying low hydraulic pressure to the material for a few seconds gases form, as is well-known, and become trapped between the material and the platens immediately above and below the material. These gases must be allowed to escape before high hydraulic pressure is applied in order to prevent distortion or rupture of the material. The usual but not always entirely satisfactory practice heretofore used is merely to decrease the press pressure on the platens to the exact point that will counterbalance the moving weights, i. e., the movable platens and material, but will not permit the topmost movable platen to drop away from the stationary platen affixed to the crosshead. This relaxation of the pressure which is known as the breathing or degassing operation permits the gases to escape despite the dead weight of the platens on the material. The importance of attaining a precise degree of control of the hydraulic pressure on the platens, which is extremely difficult in the conventional platen press, lies in the fact that, in the case of some materials, such as, for instance, that required in the making of plywood, should such hydraulic pressure be decreased too much and the uppermost movable platen be allowed to fall away from the fixed platen, even to a small extent, to leave a space between the material and the fixed platen, the trapped gases between said material and the topmost movable platen would be able to raise the material and slide it out of its centered position on the movable platen. Such difficulty is of course experienced only in the case of the material between these two uppermost platens, the material on each of the other movable platens being held against such displacement by the weight of the platens or platen above the material. While the material between these two uppermost platens can, of course, and must be recentered on the topmost movable platen, in so doing there is a considerable loss of time and effort.

An object of my invention is to provide simple, positive and effective means whereby material centered on the uppermost movable platen of a

2

platen press of the type described will be prevented from being displaced by trapped gases during the breathing or degassing operation.

Another object is to provide such means whereby it will be possible to eliminate any need for precise control of hydraulic pressure on the platens for the breathing or degassing operation.

Other objects and advantages will be more apparent to those skilled in the art from the following description of the accompanying drawings in which:

Fig. 1 is a front elevation of a platen press of the type described, in open or loading position, to which my device is shown applied;

Fig. 2 is an enlarged detailed view, partly in section, showing the operation of my device when the press is in pressing position; and

Fig. 3 is a view similar to Fig. 2, showing the operation of the device when the press is in breathing or degassing position.

In the particular embodiment of the invention which is disclosed herein merely for the purpose of illustrating one specific form among possible others that the invention might take in practice, I show diagrammatically in Fig. 1 a platen press of the type described which consists essentially of a hydraulic cylinder 1, a ram 2 having reciprocating movement within the cylinder, a moving platen 3 affixed to the ram, an upper stationary crosshead 4 supported in the usual and well-known manner by four vertical tension columns 5 whose lower ends are rigidly affixed to the cylinder, and a plurality of vertically movable hot plates or platens 6 between which sheets of material 7 are placed and centered on the platens. These platens are maintained in vertical alignment between the tension columns by means of platen guides 8 affixed to the corners of the movable platens and slidably engaging the tension columns. Conventional stephangers 9 located at each corner of the movable platens space and support the platens at any desired intervals through progressively shorter lugs 10 of the platen guides engaging progressively longer steps 10a of stephangers 9. Secured to crosshead 4 is a usual heat insulating plate 11. However, instead of employing a platen that is immovably affixed to crosshead 4, as in the case of conventional platen presses, I use instead a floating platen 12 positioned between and in vertical alignment with insulating plate 11 and the uppermost of movable platens 6, and adapted and arranged to have vertical movement as in the case of the movable platens and thereby be able to utilize the weight of the uppermost platen for degassing purposes. While any of several simple ways may be employed to mount floating platen 12 so as to allow it also to be raised and lowered by the moving ram; I prefer, for the sake of simplicity and inexpensiveness of construction, to suspend this floating

platens by a number of vertically disposed rods, each having an enlarged end, such as, for example, inverted stud bolts 13, screwed into or otherwise secured to, and rigidly pendent from, the underside of crosshead 4. These stud bolts pass freely through vertically drilled holes in extended portions of edges of the floating platen, such as, for instance, lugs 14 secured to or integrally formed with at least two sides of floating platen 12 so that the floating platen may be moved upwardly by the pressure of the moving ram and downwardly by gravity. When the press is in open or loading position, as shown in Fig. 1, the heads of stud bolts 13 carry the weight of floating platen 12 through lugs 14. The shanks of bolts 13 are of such length that, with the press in open position, there may be a small space 15 between insulating plate 11 and floating platen 12. Platen guides 3 and platen supporting means 9, incident to each of movable platens 6, may of course be dispensed with in the case of the uppermost or floating platen 12, as the shanks of stud bolts 13 maintain said platen in vertical alignment with movable platens 6.

In the operation of my device, after material has been centered on the platens, the press is closed by the introduction of low hydraulic pressure into cylinder 1, in usual manner. Such pressure causes ram 2 and moving platen 3 to be moved upwardly. Moving platen 3 then successively raises movable platens 6 off their respective supports 10a, commencing with the lowermost platen until all movable platens 6 have been so collected on moving platen 3 and the material centered on each movable platen 6 is in engagement with the underside of the platen immediately above it. In the case of the uppermost movable platen 6, the material centered thereon engages the underside of floating platen 12 and lifts the platen so that its weight is thereby transferred from the heads of stud bolts 13 to the upwardly moving pile of platens. Space 15 is eliminated when the upperside of floating platen 12 comes into contact with insulating plate 11, as shown in Fig. 2, when hydraulic compression of the material begins. Such pressure is at this time of a low value for after only a few seconds of heat and pressure to the material the gases which have begun to form must be allowed to escape before any further compression is applied. To free these gases from between the material and the platens above and below the material, such hydraulic pressure on the platens and material is slightly decreased, allowing movable platens 6 and floating platen 12 to move downwardly by gravity and causing space 15 between insulating plate 11 and the material on the uppermost platen of movable platens 6 to reappear, as shown in Fig. 3. While the platens may be so lowered to any point before drilled lugs 14 come into contact with the heads of guide bolts 13, the platens are as a practical matter lowered a distance sufficient only to free all the platens and materials of such hydraulic pressure. It will be seen that at no time throughout this breathing or degassing operation has any of the material 7 been relieved of the pressure of floating platen 12, as it would have been had said platen been immovably affixed to crosshead 4 as heretofore. The result is that the material between floating platen 12 and the uppermost of movable platens 6 is held in its original centered position on uppermost movable platen 6, and in spite of the pressure of escaping gases, by the continuous weight of floating platen 12

on the material. The material of course remains so centered while the press is again closed and the requisite amount of high hydraulic pressure is applied to the platens and to the material in the usual manner. It is also seen that the need for attaining precise control of hydraulic pressure on the platens during this degassing operation, which is imperative in the usual platen press, has been eliminated as a result of the device described herein.

From the disclosure herein, it is seen that I have provided a simple and efficient, though inexpensive, means of eliminating in a platen press the displacement of material between the two uppermost platens during the breathing or degassing operation.

It will of course be understood by those skilled in the art that various changes may be made in the construction and arrangement of parts without departing from the spirit of the invention as set forth in the appended claims.

I claim:

1. In a platen press of the type having a cylinder, a ram therein, a stationary crosshead, a plurality of vertically movable platens positioned between the ram and crosshead, and means for supporting said movable platens in spaced relation to each other when the press is in fully open position but adapted to allow the weight of such platens to remain on material between said platens when the press is partially open during a degassing operation comprising, in combination, a vertically floating platen disposed immediately below said crosshead and above the uppermost one of said movable platens, said floating platen being supported upwardly against the crosshead solely by the ram force so as to be freely separable from said crosshead and openly spaced therefrom when the press is open whereby said floating platen may follow down the other platens during said partial degassing opening of the press and thereby allow the weight of said floating platen to be maintained on the material between the floating platen and the uppermost one of said movable platens, and means for supporting the weight of the floating platen so that when the press is fully opened material may be removed from or inserted between the platens.

2. The combination set forth in claim 1 further characterized in that the means for supporting the weight of the floating platen when the press is in fully open position consists of vertical rods dependently supported by the crosshead and having enlarged ends on which the weight of the floating platen rests when the press is open.

3. The combination set forth in claim 2 further characterized in that the vertical rods have shanks of such length as to allow the weight of the floating platen to remain on the movable platens during the degassing operation and to be transferred to the enlarged ends of the vertical rods only when the press is opened a distance greater than that required for the degassing operation.
